UNITED STATES PATENT OFFICE.

CARL R. ENGLUND, OF EAST ORANGE, NEW JERSEY, ASSIGNOR TO WESTERN ELECTRIC COMPANY, INCORPORATED, OF NEW YORK, N. Y., A CORPORATION OF NEW YORK

RADIOTELÉPHONY.

1,245,446.

Specification of Letters Patent.

Patented Nov. 6, 1917.

Application filed March 29, 1916. Serial No. 87,509

To all whom it may concern:

Be it known that I, CARL R. ENGLUND, a citizen of the United States, residing at East Orange, in the county of Essex and State of New Jersey, have invented certain new and useful Improvements in Radioteléphony, of which the following is a full, clear, concise, and exact description.

This invention relates to radio telephony and in particular to a means for the transmission of modulated high-frequency waves. Its objects are to provide more efficient transmission and to improve the quality of the signals received. These objects are accomplished by preventing the radiation from the antenna of the unmodulated portion of the high-frequency wave.

It has been customary in radio telephony to transmit signals by causing the primary modulating source, for example microphone, to produce variations in the amplitude of a high-frequency wave. As is well known, if the frequency of the carrier wave is C cycles per second and the frequency of the signal to be transmitted S cycles per second, there will be radiated into the ether a complex wave which is made up of three components of frequencies $C-S$, C , $C+S$, and these components may be considered to be radiated independently. It will be evident that the unmodulated component of carrier frequency C , since it does not contain the signal frequency S , need not be present in the antenna, but may be supplied by an auxiliary source at the receiving station. This method for the transmission of signals has been previously proposed and has the advantage that the waste of energy, due to the presence in the antenna of currents of the frequency C , is eliminated. A further advantage is a slight improvement in the quality of the received signals.

The present invention provides another method of eliminating from the antenna the unmodulated component of frequency C . The manner in which this is accomplished will be explained in connection with the drawings, in which Figure 1 represents a transmitting station embodying this invention, and Fig. 2 a receiving station constructed to cooperate with the sending station of Fig. 1. This receiving station does not form a part of this invention.

Referring to Fig. 1, 1 represents a high frequency generator of any suitable type,

and 2 a transformer by means of which this generator is connected to the input circuit of a thermionic modulator 3. 4 is a microphone circuit which, by means of transformer 5, is also connected to the input circuit of the modulator 3. The output circuit of this modulator, in which there will appear the high-frequency waves of modulated amplitude, contains one winding of the transformer 6 whose other winding is connected to the network 7, 8, 9, 10. In this network 7, 8 and 9 are resistances, and 10 is a branch containing an inductance coil and a condenser by which it may be tuned. In practice, the network is so adjusted that at the carrier frequency C the potential difference between the common point of 7, 8 and that of 9 and 10 is equal to zero, and consequently at that frequency no current appears in the primary of the transformer 11. The secondary circuit of transformer 6 and the primary circuit of transformer 11 are therefore conjugate at the carrier frequency. On the other hand, if the frequency is different from that of the generator 1, the bridge network 7, 8, 9, 10 becomes unbalanced and these windings are no longer conjugate. By this arrangement, therefore, currents of frequency different from the carrier frequency produce an effect upon the input circuit of the amplifiers 12, which effect can be produced only when the wave of carrier frequency is being modulated, that is, when speech is being transmitted. The output circuit of amplifiers 12 is connected through a transformer to the common input circuit of the power amplifiers 13 whose common output circuit is coupled to the radiating antenna 14. It will be clear that current can appear in this antenna only when the wave of carrier frequency is being modulated.

Referring to Fig. 2, 16 represents a receiving antenna to which is coupled the tuned circuit 17. This tuned circuit is connected to the input side of a thermionic detector 18 whose output circuit contains a translating device 19 such as a telephone receiver. Since the component of frequency C has been eliminated from the radiating wave, it will be necessary to supply waves of this frequency at the receiving station, and this is accomplished by means of the auxiliary generator 20 in circuit with a coil 21 which may be coupled to the circuit

17 of the receiving station. While this invention has been shown as applied to a wireless signaling system, it is to be understood that it may be equally well applied 5 to signaling over wires in which modulated high-frequency oscillations are used.

What is claimed is:

1. A radio transmitting system comprising in combination, means for producing oscillations of carrier frequency, means for modulating said oscillations in accordance with signals to be transmitted, two circuits mutually conjugate to oscillations of carrier frequency, one of said circuits being connected to said modulating means, and a transmitting circuit connected to the other of said conjugate circuits. 10

2. A radio transmitting system comprising in combination, means for producing oscillations of carrier frequency, means for modulating said oscillations in accordance with signals to be transmitted, a network including two branches mutually conjugate to oscillations of carrier frequency, said modulating means being associated with one of 20 said conjugate branches, and a transmitting circuit associated with the other of said conjugate branches. 25

3. A radio transmitting system comprising in combination, means for producing oscillations, means for modulating said oscillations in accordance with signals to be transmitted, two circuits mutually conjugate at the frequency of said oscillations, one of 30 said circuits being connected to said modu- 35

lating means, amplifying means connected to the other of said conjugate circuits, and a transmitting circuit connected to said amplifying means.

4. In a high-frequency signaling system, 40 means for producing oscillations of carrier frequency, means for modulating said oscillations in accordance with signals to be transmitted, two circuits mutually conjugate to oscillations of carrier frequency, one of 45 said circuits being connected to said modulating means, and the other of said circuits being connected to a transmitting circuit, in combination with a receiving station comprising a receiving circuit and a source of 50 oscillations of carrier frequency.

5. In a high-frequency signaling system, a transmitting station comprising means for producing oscillations of carrier frequency, means for modulating said oscillations in accordance with signals to be transmitted, two circuits mutually conjugate to oscillations of the carrier frequency, one of said circuits being connected to said modulating means, and the other of said circuits being connected to a transmitting circuit, in combination with a receiving station comprising a receiving circuit, a local source of oscillations of carrier frequency, and means for combining the received oscillations and the 55 locally generated oscillations. 60

In witness whereof, I hereunto subscribe my name this 28th day of March, A. D. 1916.

CARL R. ENGLUND.
